United States Patent Office

Des. 187,505

Patented Mar. 22, 1960

187,505

AIR CONDITIONER CONTROL PANEL

Joseph B. Federico, Buffalo, N.Y., assignor to Carrier Corporation, Syracuse, N.Y., a corporation of Delaware

Application July 29, 1959, Serial No. 56,990

Term of patent 7 years

(Cl. D62—4)

The figure is a front perspective view of an air conditioner control panel embodying the new design.

The essential features of the design reside in the portions shown in full lines.

I claim:

The ornamental design for an air conditioner control panel, substantially as shown and described.
